UNITED STATES PATENT OFFICE.

WILLIAM HANSON, OF CALISTOGA, CALIFORNIA.

MECHANICAL MOVEMENT.

SPECIFICATION forming part of Letters Patent No. 758,914, dated May 3, 1904.

Application filed June 26, 1903. Serial No. 163,180. (No model.)

To all whom it may concern:

Be it known that I, WILLIAM HANSON, a citizen of the United States, residing at Calistoga, in the county of Napa and State of California, have invented new and useful Improvements 5 in Mechanical Movements, of which the following is a specification.

My invention has for its object to produce a mechanical movement or driving power for 10 operating light machinery and performing other work where a steady and evenly-running motion is desired; and the invention comprises certain novel construction and combination of parts and mechanism, as hereinafter described 15 and afterward pointed out in the claim at the end of this specification.

The construction and operation of my improved mechanism will be understood more clearly by referring to the accompanying 20 drawings, in which—

Figure 1 is a side elevation of a machine embodying my invention. Fig. 2 is an enlarged view in elevation of the central rocking lever, parts of the lever being broken away 25 and its central portion being in section to illustrate its support on the main shaft. Fig. 3 is a top plan view of the mechanism shown in Fig. 1. Fig. 4 is a view, partly in plan and partly in horizontal section, of the parts supported upon one of the shafts *s*.

The principal parts of this machine comprise a main driving-shaft *a*, two winding-drums *b*, carrying cords *c* with heavy weights *d d* on their ends, and means connecting each 35 drum with an oscillating lever *e*, through the movements of which the drums are turned in the proper direction to wind up the weights. The drums *b* are connected with the belt-carrying pulleys *f f'* in a manner to be described, 40 and these in turn are connected by the belts *g g'*, the pulleys *v v'*, and other connecting-gearing, to be later described, with the main shaft *a*, so that the power from both descending weights *d* operates to turn the main shaft.

The means for winding up the weights consist of rocking levers *e e*, mounted loosely on the shafts *s s* and carrying pawls *i*, arranged 45 to engage with the ratchet-wheels *k*, secured to the shafts *s*. The levers *e* are connected

by rods or links *t* with an oscillating lever *h*, 50 that is mounted so as to turn freely upon the shaft *a*. The ratchet-wheels *k* and the drums *b*, from which the weights are suspended, are secured fast to their respective shafts *s*, while the pulleys *f f'* are loosely mounted thereupon, but have connection with their shafts and through it with the drums by means of ratchet-wheels *p*, secured to the shaft, and pawls *n*, carried by the pulleys. It will be seen that if the lever *h* be oscillated it will operate to rock the levers *e e* and they in turn through the pawls *i*, which they carry, and the ratchet-wheels *k*, engaged thereby, will operate to turn the shafts *s* and the drums *b* in directions to wind up the weights *d*. When 65 this is being done, the pulleys *f f'* will remain stationary. On the other hand, when the weights operate to turn their shafts motion will be communicated from the latter through the ratchet-wheels *p* and the pawls *n* to the 70 pulleys *f f'*. A belt *g* connects the pulley *f* with a pulley *v* on the main shaft *a*, while the pulley *f'* is connected by a belt *g'* with a pulley *v'*, fast on a short shaft *y*, that is connected with the shaft *a* by spur-gearing 75. This manner of connecting the second belt-pulley instead of placing it directly on the shaft *a* is done to reverse the motion of that pulley and apply it to the shaft *a* in the proper manner to act in harmony with the other pulley, and thus cause both pulleys to act on the shaft *a* in the same direction.

Power is applied to the lever *h* to rock it on its center by connecting with the shaft *n* by means of a crank and a connecting-rod *5*, having one end attached to the lever *h* at a point below its fulcrum and connected at the opposite end to the crank-pin *4*. The latter is fixed in a disk *6*, fast on the end of the shaft, and a hand-crank *7* is provided in the end shaft for 90 turning it. As thus constructed and arranged the descending weights act through the drums, pulleys, and belts to rotate the shaft *a* in the same direction, while the movements of the oscillating lever *h*, acting through the rocking levers *s* and their pawl-and-ratchet wheel connections, turn the shafts in the proper direction to wind the cords on the drums.

A belt-pulley 8 on the shaft *a* furnishes means for carrying the power for the pulley to a distant point where it is required for use.

Having thus described my invention, what I claim as new, and desire to secure by Letters Patent, is—

The herein-described mechanical movement comprising the driving-shaft; oscillating lever; crank and connecting-rod connecting said lever with the driving-shaft; a pair of shafts each carrying a winding-drum, a cord and weight to each drum, and a rocking lever; pawl-and-ratchet mechanism connecting each

rocking lever with the shaft upon which it is supported; means connecting the oscillating lever with both rocking levers; a driven shaft, and pulleys and belts connecting the two drum-shafts with the last-named shaft to rotate it in the same direction.

In testimony whereof I have signed my name in the presence of two subscribing witnesses.

WILLIAM HANSON.
